CONTAINER AND PARTS THEREOF

Philip Zalkind, New York, N. Y.

Application February 1, 1936, Serial No. 61,859

7 Claims. (Cl. 129—26)

My invention relates to a novel follower, and more particularly, relates to a follower for use with collapsible containers.

This application is a continuation in part of my copending application Serial No. 693,841 covering "Container and parts therefor" filed Oct. 16, 1933 in which is claimed certain structural features relating to a collapsible container.

The use of a follower in filing containers is well known in the art. However, the use of such followers has been confined to relatively expensive casings adapted to be delivered in set up condition. In such containers various means are available for retaining the follower in position. Such means are not available in a collapsible file drawer constructed of sheet material and folded along score lines for shipment.

The object of my invention is to provide novel follow blocks that are particularly adapted for use with collapsible file drawers. By my novel construction, I provide means for supporting the follower in a drawer, and means for retaining the follower in proper position within the drawer. Further objects of my invention are thus to provide a follower with novel retaining means. A further object of my invention is to provide a follower of simple construction and low manufacturing costs and at the same time one which may be shipped with a container in collapsed condition and which will take no appreciable space in the package.

There are other objects of my invention which together with the foregoing will appear in the detailed description following in connection with the drawing in which:

Figure 1 is a perspective view of my follower in which the follower is retained in position by a metallic reinforcing structure on the bottom of the follower.

Figure 2 is a perspective view, partly broken away, showing my follower in position in a collapsible drawer.

Figure 3 is a view similar to Figure 1 showing a modified form of follower.

Figure 4 is a view similar to Figure 2 showing the follower of Figure 3 in position in a drawer.

Figure 5 is a view similar to Figure 1 showing another modified form of my follower.

Figure 6 is a view similar to Figure 2 showing the follower of Figure 5 in position in a drawer.

Referring now more specifically to Figure 1, I have disclosed one form of my follower. In this form of my follower, a corrugated board or the like 1, with metal reinforcing members 2 and 3 secured thereto along the top and bottom edges,

is originally made somewhat narrower than the width of the drawer 5 as shown in Figure 2. Metal edge 2 secured to the blank 1 protrudes from the edges as shown, a sufficient distance so that it is seated on the upper edge of the side walls of the drawer. The lower reinforcing member 3 is provided with the pointed ends 4 which seat themselves between the lower edges of the side walls and the bottom of the drawer.

In Figure 3, I show another form of my invention wherein a flexible flap or apron 6 preferably of paper material is secured to the lower edge of the follow block. As shown in Figure 4 the follow block is so placed in the drawer that the contents of the drawer adjacent the follow block, resting in this flap 6 act to hold the follow block in position.

As shown in Figure 5, in a still further modified form of my follower, I may provide in addition to the flap 6 side flaps 7 and 8 which function as legs for further supporting the follow block in position in the drawer, and which are applied as illustrated in Figure 6.

In Figures 2, 4, and 6, wherein my follower is illustrated in conjunction with a drawer, I have shown a form of collapsible drawer of sheet material which may be manually folded on score lines so that it may be stored or shipped in collapsed condition. Such a form of drawer is shown in my copending application S. N. 631,682, filed Sept. 3, 1932 and in my U. S. Patent No. 1,946,516 dated February 18, 1934 which matured from application S. N. 631,682.

It will be obvious that, since the drawer described in said application and patent is intended to be made of sheet or fiber material, the material of such drawer will be slightly flexible and elastic.

Referring now to Figures 2, 4 and 6, in which similar numbers represent similar parts, the rear portion of one of the embodiments of a drawer in combination with which my follow-block is intended to be used is shown. This drawer, has an end wall 14, tongues 9 and 13 extending from said end wall, outer side walls 10 and inner side walls 11 as an integral extension of said outer side walls and being united therewith along predetermined fold lines 12 about which said inner walls 11 may be manually folded to be adjacent to said outer walls 10, and which may be held in position in a suitable manner. Since the material at the fold lines 12 has elasticity by reason of the nature of the material, the inner walls 11 will tend to move inward into the drawer. Also since the inner flap 11 is held only at the ends thereof

adjacent to the end walls, there is nothing in the drawer structure itself which inhibits the slight inward bulging of the inner flap at its center and at other intermediate points not adjacent to the 5 end walls.

It will thus be obvious that a follow block 1 of any of the forms described will, in addition to other means which may be provided, be held in place by the slight bulge or inward movement of 10 the inner walls, particularly if the width of such follow block is only slightly less than the distance between the two inner walls 11, 11 when such walls lie against the tongues 9 and 13 and their outer walls 10.

15 It will be obvious that other forms of follow blocks come within the spirit of my invention; and although, in illustrating my invention, I have shown certain applications thereof, it will be obvious that there are many other uses, and that the 20 parts may be modified without departing from the spirit of my invention. Accordingly, I do not wish to be limited by this description, but only by the appended claims.

I claim:

25 1. In combination, a collapsible drawer of sheet material, and a follow block for said drawer; said drawer having outer side walls, inner side walls as integral extensions of said outer side walls, and being united therewith along predetermined fold 30 lines about which said inner walls may be manually folded to lie adjacent to said outer side walls, the material at said fold lines having elasticity and acting to move said inner walls inwardly into said drawer; said follow block comprising a blank 35 of sheet material somewhat narrower than the distance between the inner side walls of the drawer when the latter are in contact with the outer side walls of the drawer, but of sufficient width to be in contact with both of said inner 40 walls under the elastic action of the connection between the inner and outer walls.

2. In combination, a collapsible drawer of sheet material, and a follow block for said drawer; said drawer having outer side walls and inner side 45 walls as integral extensions of said outer walls, and being united therewith along predetermined fold lines about which said inner walls may be manually folded to lie adjacent to said outer side walls, the material at said fold lines having elasticity 50 and acting to move said inner walls inwardly; said follow block comprising a blank of sheet material somewhat narrower than the distance between the inner side walls of the drawer when the latter are in contact with the outer side walls of 55 the drawer, but of sufficient width to be in contact with both of said inner walls under the elastic action of the connection between the inner and outer walls, said follow block also having reinforcing on the top edge of said blank, said reinforcing being of sufficient length to rest on the top edges of the side walls of said drawer to maintain the top edge of the follower in predetermined 60 relation to the top edges of the side walls.

3. In combination, a collapsible drawer of sheet 65 material, and a follow block for said drawer; said drawer having outer side walls and inner side walls as integral extensions of said outer walls, and being united therewith along predetermined fold lines about which said inner walls may be 70 manually folded to lie adjacent to said outer side walls, the material of said fold lines having elasticity and acting to move said inner walls inwardly; said follow block comprising a blank of sheet material somewhat narrower than the distance 75 between the inner side walls of the drawer

when the latter are in contact with the outer side walls of the drawer, but of sufficient width to be in contact with both of said inner walls under the elastic action of the connection between the inner and outer walls, said follow block also having means along its top edge to hold the top edge at a fixed height relative to the side walls of the drawer, and an apron along its bottom edge to lie in contact with the bottom of said drawer. 5

4. In combination, a collapsible drawer of sheet 10 material, and a follow block for said drawer; said drawer having outer side walls and inner side walls as integral extensions of said outer side walls, and being united therewith along predetermined fold lines about which said inner walls may 15 be manually folded to lie adjacent to said outer side walls, the material of said fold lines having elasticity and acting to move said inner walls inwardly; said follow block comprising a blank of sheet material somewhat narrower than the distance 20 between the inner side walls of the drawer when the latter are in contact with the outer side walls of the drawer, but of sufficient width to be in contact with both of said inner walls under the elastic action of the connection between the inner and outer walls, said follow block also having means for holding its top edge at a fixed height 25 relative to the side walls of the drawer, an apron along its bottom edge to lie in contact with the bottom of the drawer, and extensions along its 30 side edges to lie in contact with the inner side walls of the drawer.

5. A follow block adapted to be shipped as a substantially flat form to be set up by the user for use in a drawer; said follow block comprising a 35 blank of stiff paper material, a sheet of flexible paper material adhesively affixed to one face of said blank and extending beyond the bottom edge of said blank, the extension being adapted to lie in contact with the bottom of said drawer when the follower is applied to the drawer, and a V shaped metallic member somewhat longer than the width of said blank gripped around the upper edge of said blank, the ends of said metallic member being adapted to lie in contact with the upper 40 edges of the side wall of the drawer to support the top of the follower when the follower is applied to the drawer. 45

6. A follow block adapted to be shipped as a substantially flat form to be set up by the user 50 for use in a drawer; said follow block comprising a blank of stiff paper material, a sheet of flexible paper material adhesively affixed to one face of said blank and extending beyond the bottom edge of said blank, the extension being adapted to lie 55 in contact with the bottom of the drawer when the follower is applied to the drawer, wing extensions from the side edges of said blank and manually foldable at substantially right angles thereto to lie in face to face contact with the side walls 60 of the drawer when the follower is applied to the drawer, the said wing extensions being adapted to function as legs to aid in supporting the follow block in its position in the drawer and a V shaped metallic member somewhat longer than the width 65 of said blank gripped around the upper edge of said blank, the ends of said metallic member being adapted to lie in contact with the upper edges of the side wall of the drawer to support the top of the follower when the follower is applied to the 70 drawer.

7. In combination, a collapsible drawer of sheet 75 material having side walls tending to move inwardly toward each other; a follow block comprising a blank of sheet material, somewhat

narrower than the normal distance between the side walls before being flexed inwardly toward each other but of sufficient width to contact and limit the inward movement of said side walls when said walls are subjected to inward movement; means extending along the top edge of said follow

block for holding the top edge at a fixed height relative to the side walls of the drawer; and an apron along the bottom edge to be in contact with the bottom of said drawer.

5

PHILIP ZALKIND.
